UNITED STATES PATENT OFFICE.

JOSEPH LEDUC AND NAPOLEON GOBEILLE, OF ST. HYACINTHE, QUEBEC, CANADA.

GAS HEATING APPARATUS.

1,393,227.

Specification of Letters Patent. Patented Oct. 11, 1921.

Application filed January 16, 1919. Serial No. 271,409.

(GRANTED UNDER THE PROVISIONS OF THE ACT OF MARCH 3, 1921, 41 STAT. L., 1313.)

To all whom it may concern:

Be it known that we, JOSEPH LEDUC, residing at 11 Laframboise street, St. Hyacinthe, Quebec, Canada, and NAPOLEON GOBEILLE, residing at 30 Bourdage street, St. Hyacinthe, Quebec, Canada, have invented certain new and useful Improvements in Gas Heating Apparatus; and we do hereby declare that the following is a full, clear, and exact description of the same.

The present invention relates to improvements in gas heating apparatus and one of the objects of the invention is to devise an apparatus of this character that is adjustable to practically any size of furnace or stove, as well as to provide means for extinguishing the ignited burners.

A further object of the invention is to provide a fuel tank of comparatively simple construction equipped with filtering means.

Another object is to provide an apparatus of this character in which a plurality of longitudinal strands of metal are utilized to facilitate the conversion of the oil into gas.

A further object is to provide a plurality of metal strands of one kind intermingled with a plurality of strands of a different metal such as copper.

30 A further object of the invention is to provide a device of this character simple of construction, cheap to manufacture and extremely economic, in order that it may be available to all classes.

35 The invention will be readily understood with the aid of the accompanying drawings in which:

Figure 1 is a perspective view of the apparatus and fuel tank.

40 Fig. 2 is a vertical sectional view of the tank.

Fig. 3 is a perspective view of a modified form of the apparatus.

Fig. 4 is a cross section on line A—A of 45 Fig. 1.

Fig. 5 is a perspective view of a further modified form of the apparatus.

50 Fig. 6 is a side elevation of the apparatus disclosing the intermediate reservoir and side burners.

Fig. 7 is an enlarged side elevation of the intermediate reservoir and side burner.

Fig. 8 is a longitudinal section through the main connecting chamber used in the

modified form of apparatus disclosed in 55 Fig. 5.

Like numerals of reference indicate corresponding parts in each figure.

In the drawings, 1 is a rectangular base comprising four upright posts 2 at each corner of said base, each of said posts having a series of notches 3 on one side thereof.

4 is a rectangular frame comprising two end cross bars 5 which are adapted to engage said notches 3 on the posts 2 and two 65 longitudinal bars 6 connecting said end cross bars. 7 is a plate closing the open inner space between said bars 5 and 6.

At one end of said frame 4, is rigidly secured a vertical bracket 8, adapted to support the U-shape pipe 9, and 10 are burner openings in the lower branch of said pipe. 11 are baffle plates slidable and adjustable on the upper branch of said pipe, and 12 are choking blocks slidably mounted on the 75 lower branch of the pipe.

The upper branch of the U-shaped pipe 9 is preferably provided inside with a plurality of longitudinal strands or wires of iron 13, and suitably secured therein are 80 filters which are not disclosed in the drawings.

Intermingled with the iron wires 13 are a plurality of copper wires 13^a of slightly larger diameter and running parallel to said 85 wires, 13. These copper wires being more easily heated than the iron wires, will quickly convert the oil into gas. Further, a recess 13^b is provided at one end of the pipe 9 to permit the accumulation of the oil and 90 to provide an even feeding, by cutting out the ends of the wires as disclosed in Fig. 6 of the drawings.

On the lower branch of the pipe 9 intermediate thereof, is secured a T-connection 95 14^a provided in one side of its stem portion with an opening 14^b, and 14^c is a nut threaded in said stem portion of the T-connection and adapted to close the opening 14^b when screwed in far enough. It will thus be readily seen that if the nut 14^c is unscrewed the gas will escape through said opening 14^b and a side flame may thus be obtained to heat, for instance, in a stove, the oven.

The lower branch of the pipe 9 is free 105 of strands or wires in order that the expanded gas may circulate freely.

A fuel tank 14 adapted to be hung or sus-

pended on a wall, is provided having there-in a vertical water tube 15 which projects through the bottom of said fuel tank and is provided at its lower end adjacent the bottom of said tank with a plurality of holes 15^a. 16 is a closed compartment having two openings 17 and 18 in alinement and adjacent the bottom of said tank said openings being closed by nettings adapted to strain 10 the petroleum before it enters the pipe 15. 19 is a pipe connecting said pipe 15 to the U-shaped pipe 9, and 20 is a valve for controlling communication between pipes 15 and 19. 21 is a cover preferably provided 15 on top of said tank 14.

In Fig. 3 is disclosed a modified form of burner-pipe, and an extensible base which consists of a frame 22 having four downwardly depending legs 23 on which are fitted 20 hollow slideable extension legs 24 adapted to be extended or contracted at will and to be secured in place by the screws 25.

Mounted on said frame 22 are three U-shaped pipes 26 each upper branch being 25 connected to a cross pipe 27. 28 is a pipe suitably connected at one end to said pipe 27 and adapted to be connected at its other end to the fuel supply tank. Burner openings 29 and baffle plates 30 are also provided. 30 This modified form of apparatus is particularly adapted for use in furnaces and is adjustable to any size of fire box, as well as the apparatus disclosed in Fig. 1 of the drawings.

35 In said modified form of apparatus, each of the burner openings is controlled by a screw 31 which is threaded in the lower branch of said pipe 26, and made to come in alinement with the corresponding burner 40 opening so that by screwing or unscrewing said screw 31, the opening may be closed or opened, the same arrangement being also adopted with respect to the openings 10 in pipe 9. Thus the flame may be regulated 45 to the wants of the furnace to be heated with a minimum quantity of oil.

It will be understood, of course, that the

multiple pipe system disclosed in Fig. 3 may be employed in connection with the form of supporting frame illustrated in Fig. 50 1, and likewise that the single pipe 9 may be employed with the frame 22 represented in Fig. 3, such arrangement obviously requiring no separate illustration.

In Fig. 5 is illustrated another modified 55 form of apparatus wherein the principle is the same as used in the previous constructions. In this modification of the apparatus, the oil enters one of the branches of a four branch connection 32, said connection being 60 divided by a partition 33, in order that the oil as it enters the upper branch 34 of the pipe will be forced to circulate entirely through said upper branch 34, before passing through the pipe 35 leading to the lower 65 branch 36 which is provided with a plurality of burner openings 37.

What we claim as our invention is:

1. In a gas heating apparatus, the combination of a polygonal base provided at each 70 corner with an upstanding post formed with a vertical series of teeth; a supporting frame adjustably engaged with said teeth; and a generating pipe mounted on said base and having fuel supply means connected to it. 75

2. In a gas heating apparatus, the combination of a rectangular base provided at each corner with an upstanding post formed with a vertical series of teeth; a rectangular supporting frame comprising a pair of cross 80 bars adjustably engaged at their ends with the teeth on the adjacent posts and a pair of longitudinal bars connecting said cross bars; and a generating pipe mounted on said base and having fuel supply means connected 85 to it.

Signed at Montreal, Quebec, Canada, this 15th day of April, 1918.

JOSEPH LEDUC.
NAPOLEON GOBEILLE.
